UNITED STATES PATENT OFFICE.

EDWARD I. BRADDOCK, OF WINCHESTER, MASSACHUSETTS, ASSIGNOR, BY DIRECT AND MESNE ASSIGNMENTS, TO LAMB & NASH COMPANY, OF KITTERY, MAINE, A CORPORATION OF MAINE.

METAL HOOP.

1,190,506.

Specification of Letters Patent. Patented July 11, 1916.

Application filed November 14, 1914. Serial No. 872,245.

To all whom it may concern:

Be it known that I, EDWARD I. BRADDOCK, a citizen of the United States, residing in Winchester, county of Middlesex, and State 5 of Massachusetts, have invented an Improvement in Metal Hoops, of which the following description, in connection with the accompanying drawings, is a specification, like characters on the drawings representing like parts.

This invention relates to a metal hoop for barrels, tubs, pails and the like, and has for its object to provide an inexpensive, strong, and light hoop for the purpose specified. 15 To this end, the metal hoop comprises a sheet metal member in the form of a substantially narrow continuous band having a fold to form a hollow bead, and also having a series of arms extended from the unfolded portion of said band, said arms being spaced apart and connected together by a wire member. The hollow bead contains 20 within it a reinforcing wire, which for the best results has its ends welded together and 25 to the hollow bead, and the ends of the latter are also welded together. The wire member, which connects the arms extended from the band, has its ends connected together to form a wire hoop and said ends are for the 30 best results welded together. These and other features of this invention will be pointed out in the claims at the end of this specification.

Figure 1 is an elevation of the upper portion of a barrel provided with a metal hoop embodying this invention. Fig. 2, a plan of the barrel and hoop shown in Fig. 1. Fig. 3, a detail in elevation and on an enlarged scale of a portion of the hoop shown in 35 Figs. 1 and 2. Fig. 4, a view like Fig. 3 with the hoop curved to conform to the taper of the barrel. Fig. 5, a section on the line 5—5, Fig. 4. Fig. 6, a detail of the sheet metal member before it is folded to 40 form the hollow bead. Fig. 7, a modification to be referred to, and Fig. 8, a detail to 45 be referred to.

Referring to the drawing α represents a barrel provided with a metal hoop embodying this invention. The metal hoop comprises a sheet metal member in the form of a substantially narrow continuous band b , see 50 Figs. 3 and 4, which is provided with a fold to form a hollow bead c , within which is

located a reinforcing wire d . The metal 55 band b has extended from its unfolded portion a series of arms 10, which are separated by spaces 12 preferably of a width and shape the same as the arms 10. The arms 10 are connected together near their outer ends 60 by a wire member 13, which may be secured to the said arms by tongues 14, which are punched out of the arms and bent or folded over upon the wire 13, to leave the latter loose or free to permit movement of one 65 with relation to the other.

The sheet metal member b is bent into the form of a hoop and has its ends fastened together, preferably by electrically welding the ends of the bead together and the ends 70 of the reinforcing wire d together and to said bead, as indicated by 20 in Figs. 1 and 2, and the wire member 13 also has its ends secured together, preferably by electrical welding, as indicated by 21 in Figs. 1 and 2. 75

The loose wire 13 is made longer than the wire d , so that when the ends of the wire 13 are welded or otherwise connected together, it will permit the lower portion of the sheet metal member to be enlarged in diameter, 80 so that the completed hoop is in such form that it may be readily driven onto the tapered barrel, without subjecting to detrimental strain either the sheet metal member or the wire hoop formed by the wire member 13. The sheet metal member b may and 85 preferably will be made by cutting a sheet metal strip, not shown, into duplicate blanks, like that shown in Fig. 6. In this manner a very material saving in the cost 90 of the sheet metal member of the hoop is provided for, as there is no waste of stock. In reinforcing the sheet metal member b , the wire d is applied to the continuous upper portion of the said member, and the 95 upper edge portion thereof is folded over upon the wire after the manner represented in Figs. 1, 2 and 5, to form the hollow bead.

In practice, a plurality of sheet metal members b may be applied in succession to 100 a continuous wire d , as represented in Fig. 8, so as to overlap and form a reinforced sheet metal member of substantial or continuous length, which is then cut up into strips or lengths, according to the size or 105 diameter of the hoop to be made from it, and the reinforcing wire d may be secured in fixed relation to the hollow bead when

the continuous strip is being formed, by providing one or more crimps in the said bead as indicated in Figs. 1 and 8 at 3°.

The loose wire 13 is then applied to the 5 lower portion of the sheet metal member, and may be secured thereto by the fingers 14, which are punched out of the arms and folded or bent over the wire 13, so as to attach it to the said arms, and thus attach it 10 to the sheet metal member, or the ends of the arms 10 may be folded over upon the wire 13 as represented in Fig. 7. The sheet metal member with both wires attached thereto, is preferably given a curved form 15 so that the beaded upper portion is no longer straight as shown in Fig. 3, but is curved as represented in Fig. 4, which imparts to the lower portion of the sheet metal member a larger diameter than the beaded 20 upper portion when the ends are welded together to form the hoop. The ends of the beaded upper portion of the sheet metal member are then fastened together, preferably by electrically or otherwise welding 25 the same together and at the same time welding the ends of the reinforcing wire *d* together and to the hollow bead. The ends of the wire 13 are also fastened together 30 preferably by electrically welding them together to form a continuous hoop, which greatly increases the strength of the lower non-continuous portion of the sheet metal member. The above described hoop is not only inexpensive but is light and strong. 35 It is preferred to weld the ends of the wire 13 together, as represented in Figs. 1 and 2, but it is not desired to limit the invention in this respect, as the ends of the wire 13 may be otherwise secured together.

40 Claims:

1. A metal hoop comprising a sheet metal member provided at one edge with a fold to form a hollow bead and having extended from its unfolded edge or portion a plurality 45 of arms spaced apart, a reinforcing wire within the hollow bead, said hollow bead and reinforcing wire having their ends welded together, and a wire member secured to said arms and having its ends welded together, 50 substantially as described.

2. A metal hoop comprising a sheet metal member provided at one edge with a fold to form a hollow bead and having extended from its unfolded edge or portion a plurality 55 of arms spaced apart and provided with bent fingers integral with said arms, a reinforcing wire within the hollow bead, said hollow bead and reinforcing wire having their ends welded together, and a wire 60 member attached to said arms by said bent fingers and having its ends welded together, substantially as described.

3. A metal hoop comprising a sheet metal

member provided at one edge with a fold to form a hollow bead and having extended 65 from its unfolded edge or portion a plurality of arms spaced apart, a reinforcing wire within the hollow bead, said hollow bead and reinforcing wire having their ends welded together, and a wire member secured 70 to said arms and having its ends secured together.

4. A metal hoop comprising a sheet metal member provided at one edge with a fold to form a hollow bead and having extended 75 from its unfolded edge or portion a plurality of arms spaced apart, a reinforcing wire within said hollow bead having its ends welded together, and a wire member secured to said arms and having its ends 80 secured together, substantially as described.

5. A metal hoop comprising a sheet metal member provided at one edge with a fold to form a hollow bead and having extended from its unfolded edge or portion a plurality 85 of arms separated by spaces of substantially the same width and shape as the said arms, a reinforcing wire within the hollow bead, said hollow bead and reinforcing wire having their ends welded together, and a wire member of greater length than the reinforcing wire and secured to said arms 90 and having its ends welded together to form a wire hoop of greater diameter than the wire hoop formed by the reinforcing wire. 95

6. A metal hoop comprising a metal member provided at one edge with a fold to form a hollow bead and having extended from its unfolded edge or portion a plurality 100 of arms spaced apart, a reinforcing wire within said hollow bead having its ends welded together to form a wire hoop within the hollow bead, and a wire member attached to said arms and having its ends connected together to form a wire hoop of 105 greater diameter than the wire hoop within the hollow bead.

7. A sheet metal member provided at one edge with a fold to form a hollow bead and having extended from its unfolded edge or 110 portion a plurality of arms spaced apart and separated by spaces of a width and shape substantially equal to the width and shape of said arms, a reinforcing wire within said hollow bead, and a wire member secured to 115 said arms to permit the latter to move on said wire member and having its ends joined together to form a closed wire hoop.

In testimony whereof, I have signed my name to this specification in the presence 120 of two subscribing witnesses.

EDWARD I. BRADDOCK.
